Faulcon & Wright

UNITED STATES PATENT OFFICE.

GEORGE F. HANDLEY, OF GLENDALE, NEW YORK, ASSIGNOR TO ROYAL TYPEWRITER COMPANY, INC., OF NEW YORK, N. Y., A CORPORATION OF NEW YORK.

TYPE-WRITING MACHINE.

1,244,729.

Specification of Letters Patent. Patented Oct. 30, 1917.

Application filed December 12, 1916. Serial No. 136,433.

To all whom it may concern:

Be it known that I, GEORGE F. HANDLEY, a citizen of the United States, residing at Glendale, Long Island, State of New York, have invented certain new and useful Improvements in Type-Writing Machines, of which the following is a specification.

This invention relates to the mechanism of type-writing machines for effecting changes in the letter case printing and particularly to mechanism of this class in which a key lever is employed for shifting the platen or carriage from lower to upper case position. In such mechanism latches operated by shift keys have heretofore been employed for holding the carriage in both upper and lower case positions.

In a copending application for patent filed by Edward B. Hess, August 24, 1916, No. 116,604, which has matured into Patent 1,226,770, dated May 22, 1917, case shifting mechanism is shown in which means is provided for cushioning the movement of the shift key after the shifting operation is complete, said mechanism comprising an increased spring placed under initial compression but which is further compressed during the final movement of the shift key.

According to my invention instead of employing a spring cushion in the form shown in said application No. 116,604, I provide spring cushioning means of improved construction for a similar purpose but which enables me to use a stronger spring which is capable of better and more convenient adjustment. Instead of directly connecting the carriage supporting and raising mechanism to the shift key lever by means of a yielding link I connect said mechanism with a lever pivotally mounted on the shift key lever and connected with said shift key lever by a spring which is adjustable to vary its tension and which serves to cushion the shift key lever during its movement after the shifting operation is complete.

Letters Patent of the United States, No. 984,284, granted February 14, 1911, to the Royal Typewriter Company, as the assignee of J. F. McBirney, show case shifting mechanism in which a latch operated by the shift key is employed for holding the carriage in either its raised or lowered position, and I preferably employ such a latch. My improvements are preferably associated with

devices for locking the shift key in its depressed position.

In the accompanying drawings I have shown my improvements applied to a Royal Standard Machine of well known construction.

Figure 1 is a view in longitudinal section of the machine frame or casing and it shows the carriage and the carriage shifting mechanism in side elevation. This figure of the drawing shows the carriage in lower case position.

Fig. 2 is a detail plan view showing how two shift keys may be employed, one on each side of the machine, for raising and lowering the carriage and also shows the shift lock key associated with one of the shift keys.

Fig. 3 is a detail view in side elevation showing partly how the carriage is supported at one end by an adjustable stop when in its lowered position.

Fig. 4 is a view similar to Fig. 1 but shows the carriage in elevated position and it indicates the position of the carriage raising and lowering mechanism when the carriage is raised.

Fig. 5 is a detail view on an enlarged scale showing how the cushioning device is associated with the shift key and the links which connect it with the locking latch and the carriage raising and lowering mechanism.

Fig. 6 is a detail view showing how the shift lock key is associated with locking devices for holding the shift key in depressed position.

Fig. 7 is a view similar to Fig. 6 but shows the shift key depressed and the shift lock key in position to lock the shift key in depressed position.

The carriage A supports a platen B and is supported at its front on a shift rail C which has downwardly extending arms D connected at their lower ends to links E pivoted to the machine frame at e. Levers F are pivotally connected to the arms D near their upper ends and the rear ends of the levers are pivotally connected with the machine frame at f. It will be understood that there is a pair of links E and a pair of levers F, those on one side of the machine only being shown.

The shift lever H is pivoted at h to the

machine frame and carries a finger key h' . A shift locking lever and key I are associated with the shift key lever in the usual way. In Figs. 1 and 2 of the drawings the 5 shift lock mechanism and the locking mechanism has been omitted for the sake of clearness but it is shown in Figs. 6 and 7. The lever H is in bell crank form and is connected by a rod K with the locking latch G 10 engaging a lug d for holding the carriage in either upper case or lower case position and said lever H is connected with one of the levers F by links or rods associated with adjusting and cushioning devices of improved 15 construction which will be hereinafter described. As indicated in Fig. 2, more than one shift lever may be employed. Preferably a single locking lever is used.

A spring S connected with one of the levers F at s and adjustably connected with the machine frame at s' is employed for counterbalancing to some extent the weight of the carriage in the usual way.

The shift lock lever I operates the locking lever J pivoted to the machine frame at j and having an end j² normally engaged by a pin i on the shift lock lever I. Said lever J is formed with a recess j', and said lever is held in the position shown in Fig. 25 6 by a spring j². When the shift lever H is depressed and the levers I and J are also depressed the parts occupy the position shown in Fig. 7, when, as will be observed, the pin i', on the lever H, enters the recess j' and 30 the case shifting lever is held in depressed position. By merely depressing the shift key the pin i' will be disengaged from the lever J and the spring j² will cause the lever J and the shift lock lever to rise, thus releasing the case shift lever which will also 35 rise to normal position. The carriage will then lower and the latch will engage the lug d. The manner in which the latch G operates to hold the carriage in either elevated 40 or depressed position is similar to that described in the McBirney Patent No. 984,284, before mentioned. Normally the latch G is in the position shown in Fig. 1 and engages the lug d on one of the arms D. Said 45 latch is pivoted to the machine frame at d' and to its lower end is connected a light spring d², the opposite end of which is formed with a loop d³ surrounding a pin d⁴. When the parts are in the position shown in 50 Fig. 1, the spring is not under tension but when the carriage is raised (Fig. 4) the spring is held under tension and serves to assist in quickly withdrawing the latch from the lug d when the shift key is raised. The 55 60 indicates one of a pair of stops for limiting the upward movement of the carriage and T' indicates one of the stops for limiting its downward movement.

The shift key lever H is not directly connected with the levers F and latch G as here-

tofore, but its upturned end h³ carries a lever U having a part u substantially parallel with the upturned end of the lever and a curved or segmental portion u' extending forwardly from its lower end. The lever 70 U is pivotally connected near its lower end at u² with the lever H and it is provided about midway between its upper and lower ends with a hole or opening u³, through which extends a pin u⁴ carried by the part 75 h³ of the lever H. It will be observed that the diameter of the pin is considerably smaller than that of the opening.

A spring W is connected at one end to the upper end of the shift key lever and at its 80 opposite end it is adjustably connected with the curved or segmental portion of the lever U. The spring normally holds the lever U in the position shown in Fig. 1 at which time the pin u⁴ engages the rear wall of the 85 hole u³, but the construction is such that at the proper time, as hereinafter described, the lever U can rock on the lever H in the manner indicated in Fig. 5 against the force 90 of the spring W. The upper end of the lever U is connected by a link or rod K with the latch G and the said lever U is also connected by a rod L with one of the levers F. The connection between the rod L and the lever F is preferably made by forming a loop 95 a in the rear end of the rod which engages a pin f' on the lever F and this loop at its front end is connected with a spring g which is attached at its rear end to the pin f'. When the carriage is lifted the spring g is 100 under tension, as indicated in Fig. 4, but when the carriage is lowered the spring causes the rear end of the loop to separate from the pin a short distance so that when the shift lever is again depressed there is a 105 little lost motion before the rear end of the loop engages the pin f' and thus before the raising operation of the carriage commences. In this way time is given for the latch G to be disengaged from the carriage before the 110 latter commences to rise.

The part u' of the lever U is disposed eccentrically and this part u' is preferably toothed as indicated to facilitate the adjustment of the spring W. By varying the 115 point of connection of the spring with the arm u' the tension of the spring may be varied inasmuch as the curve of the arm is eccentric to the point x where the inner end of the spring is attached to the shift lever. 120

Fig. 1 of the drawing shows the mechanism in normal or lower case position. At this time the latch G engages the lug d so as to prevent the carriage from being accidentally or prematurely raised. If the 125 shift key lever be depressed the mechanism will assume the condition shown in Fig. 4, the latch G being first released from the lug d and then the levers F being operated so raise the carriage to the position shown. 130

The carriage is thus raised against the stops T without changing the tension of the spring W, but a further movement may be given to the shift key as indicated by dotted lines 5 in Fig. 4, and when such movement is given to the key the arm h^3 of the lever H will be given a slight additional movement, as indicated by dotted lines, while the lever U is held stationary. In this way the spring 10 W is slightly extended, as indicated in Fig. 5, the pin u^4 on the lever H moving in the hole u^5 of the lever U to the front wall of said hole which limits the movement of the pin. This slight additional movement of 15 the shift key is therefore cushioned by the spring W and the construction described enables me to employ a spring of the desired size and strength without interfering with other parts of the mechanism and the connections for the spring are such as to afford 20 a very easy adjustment.

By reference to Fig. 2 it will be observed that the carriage mechanism may be operated from either side of the machine, two 25 shift keys being employed which are attached to the rock shaft h. A single shift locking lever is preferably used which is mounted to move independently of the rock shaft. It will of course be understood that 30 when it is desired to print a series of capital letters the shift lock lever I may be depressed without having first depressed the shift key lever as the construction of the mechanism is such that the depression of the 35 lever I will cause the shift lever H to be also depressed and held until it is operated to release the locking mechanism.

I claim as my invention:

1. In case shifting mechanism for type-writing machines, a shift key lever, a yieldingly mounted lever positively connected therewith and actuated by the shift key lever, and unyielding connections between said yieldingly mounted lever and the part to be 45 shifted, thereby affording an independent additional movement of the shift key lever.

2. In case-shifting mechanism for type-writing machines, a shift key lever, an auxiliary lever carried by the shift key lever 50 and yieldingly mounted thereon, and connections between said auxiliary lever and the part to be shifted for affording an independent additional depression of the shift key lever.

3. In case-shifting mechanism for type-writing machines, a shift key lever, a yieldingly mounted auxiliary lever thereon and having a limited movement on the shift key

lever, and connections between said auxiliary lever and the part to be shifted for affording an independent additional depression of the shift key lever. 60

4. In case shifting mechanism for type-writing machines, a shift key lever, a lever carried thereby and having a projecting arm, a spring connecting said arm with the key, and connections between the lever and the part to be shifted. 65

5. In case shifting mechanism for type-writing machines, a shift key lever having an upturned arm, a lever pivotally mounted on said arm and having a projecting arm, a spring connecting said arms, means for limiting the movement of the lever on the key lever, and connections between the lever and the part to be shifted. 70 75

6. In case shifting mechanism for type-writing machines, a shift key lever having an upturned arm, a lever pivotally mounted on said arm and formed with a hole between its pivot and its upper end, a pin carried by the arm of the key lever and extending into said hole, a yielding connection between the arm of the lever and the shift key lever, and connections between the lever and the part to be shifted. 80 85

7. In case shifting mechanism for type-writing machines, a shift key lever having an upturned arm, a lever pivotally mounted on said arm and having a curved projecting arm, a spring attached at one end to the arm of the key lever and adapted to be attached at its other end to said curved arm, the curvature of which latter arm is eccentric to the point of connection of said spring to the arm 90 of the key lever, and connections between said pivotally mounted lever and the part to be shifted. 95

8. In case shifting mechanism for type-writing machines, a shift key lever carrying a yieldingly mounted lever, connections between said second lever and the part to be shifted, a latch for holding the shifted part 100 in position, and connections between the latch and said second lever. 105

9. In case shifting mechanism for type-writing machines, a shift key lever carrying a yieldingly mounted lever, connections between said second lever and the part to be shifted, a latch for holding the shifted part 110 in either normal or shifted position, and connections between the latch and said second lever.

In testimony whereof I have hereunto subscribed my name.

GEORGE F. HANDLEY.
